UNITED STATES PATENT OFFICE.

NATHAN J. PADDOCK, OF JERSEY CITY, NEW JERSEY.

ROTARY INTERNAL-COMBUSTION ENGINE.

1,197,658.

Specification of Letters Patent. Patented Sept. 12, 1916.

Application filed April 16, 1912. Serial No. 691,143.

To all whom it may concern:

Be it known that I, NATHAN J. PADDOCK, a citizen of the United States, residing at Jersey City, county of Hudson, and State of New Jersey, have invented certain new and useful Improvements in Rotary Internal-Combustion Engines, of which the following is a specification.

This invention relates to an improved rotary internal combustion engine, the object being to provide an engine of this character that is composed of a plurality of cylinders mounted upon a rotatable support or disk. The disk is rotated, and the cylinders mounted therefrom are carried around by the explosion of a combustible mixture of gas and air in one or more of the cylinders. The engine is so arranged that, during the rotation or movement of the disk by an explosion in one or more of the cylinders, certain other of the cylinders will exhaust and certain others take in a fresh mixture and compress.

In the accompanying drawings, which illustrate one embodiment of my invention, Figure 1 illustrates a sectional side view of my improved engine; Fig. 2 is a sectional plan view, the section being taken on a line 2—2 in Fig. 1; Fig. 3 is a sectional plan view, the section being taken on a line 3—3 in Fig. 1; Figs. 4, 5 and 6 are diagrammatic views of the commencement of air intake stroke, the end thereof and the end of a compression stroke respectively; Fig. 7 is an enlarged detail end view of the intake valve and casing; and Fig. 8 is an enlarged detail view of the manner of securing the intake valve operating spring to the lever for the abutment piston.

Referring to Figs. 1, 2 and 3, my improved engine comprises a rotatable disk 1 which is secured to a rotatable hollow shaft 2 by means of a key 3, the said disk being held in position on said key by means of plates 4 which are secured to the disk 1. In order to block off the bore 5 in the shaft 2, I provide a partition 6, the blocking off of the bore 5 provides two chambers, one 5^a for air only, and the other 5^b for a mixture of air and a gas which is delivered to its chamber by means of a duct 8 which is connected to a suitable carbureter not shown. The duct 7 connects the air chamber with a suitable air pump or fan, not shown.

The elements which impart movement to the disk 1 consist of cylinders 9, 10 and 11,

together with the pistons 12 and 13 in each cylinder. The cylinders are rigidly secured to the disk 1 in any desirable manner. While I have shown but three cylinders 60 more may be used if desirable and both sides of the disk 1 can carry cylinders whereby more power is obtained.

The pistons 12 and 13 have secured thereto piston rods 14 and 15 respectively, and each 65 of the said piston rods 14 and 15 are slidably supported in guides 16 and 17 respectively, in a manner shown in Fig. 3.

The piston rods 14 are each connected by links 18 to levers 19 which in turn are pivotally secured to the disk 1 as at 20. The inner end of the shorter leg of each lever 19 carries a roller 21 which rides upon a cam 22.

Each piston rod 15 is connected by a link 23, to a lever 24 pivoted to the disk 1 as at 25. The inner end of the shorter leg of each lever 24 is provided with a roller 26 which rides upon a cam 27.

By referring to Fig. 4, it will be seen that each piston rod 17 is centrally bored as at 28 in which bore an oil pipe 29 is slidably fitted. The pipes 29 lead from an oil tank 30 which is mounted upon the air drum 31. The air drum 31 communicates with the air chamber in the shaft 2 and air is conducted 85 from said drum to each end of each cylinder 9, 10 and 11 through ducts 32.

The bore 28 in each piston rod 17 leads to a chamber 33 formed in each piston 13. The lubrication of the cylinders is obtained by oil passing from the oil tank 30 to the cylinders through the pipes 29, bore 28 and oil chamber 33 then through openings 34 which lead from said oil chamber to the wall of the cylinder. The oil is forced out 95 of the chamber 30 through the pipes 29 by the force of an explosion in a working cylinder and by centrifugal force. Each cylinder is connected by a pipe 35 (see Fig. 1), with the oil tank 30 at about the time a work stroke is completed, and just before the exhaust ports 36 are opened the pipes 35 will be uncovered. The remaining pressure in the cylinder will exert part of its force on the oil in the tank 30 whereupon 105 some of the said oil will be forced into the other cylinders. In other words, at the completion of each working stroke those cylinders which are not acting to turn the disk will be lubricated.

As shown in Fig. 1, the cylinder 9 is at its firing point at which time a contact 37,

on the periphery of the disk 1, strikes a brush 38 which is included in one side of an electrical circuit, a magneto for instance, which is not shown, the other side of said circuit being grounded on the frame of the engine. There is a contact 37 for each cylinder, and each contact is connected by a wire 39 to a spark plug 40 in each piston 13. As each cylinder reaches the position A, the charge therein will be exploded as compression takes place while the cylinder is passing from about the point B to the point A, the piston rod 14 passing upward and in contact with the inclined guiding surface 41^a of an abutment 41. When a piston rod 14 reaches the seating surface 42 of the abutment 41, which is offset from the inclined guiding surface 41^a thereof, a contact 37 will strike the brush 38 at which time ignition occurs. The abutment 41 acts as a backing for the explosion and consequently the cylinder will go upwardly causing the disk to rotate. The abutment 42 is located outside the circle described by the rotating cylinders and piston rods. At about the time that the working cylinder has completed its stroke, the next succeeding piston rod 14 will contact with the abutment 41 at which time compression will take place in its cylinder. For instance, when cylinder 9 finishes its stroke, the piston 14 of cylinder 11 will strike the abutment 41 and start to compress. It will be seen by referring to Fig. 1 that each duct 32 has a pipe 43 leading therefrom to its adjacent cylinder and through one of the exhaust ports 36. When the exhaust ports are uncovered, air will flow through the pipe 43 into the cylinder. The inflow of air will extinguish any flame that may remain in the cylinder, and also will scavenge the cylinder. Should the cylinder heads be carbonized and hold fire, the air will extinguish the said fire, whereby premature explosion will be prevented when a fresh mixture is drawn in.

The cylinders and heads are cooled by the flow of air from the inturned ends of the ducts 32 as has been stated, the cylinder 9 in Fig. 1 is shown at the firing point, the cylinder 10 at the exhaust point and the cylinder 11 at the commencement of the intake stroke. For the sake of clearness, I will term the pistons 12 pump pistons and the pistons 13 abutment pistons. The abutment pistons are operated to move longitudinally into the cylinders by the cam 27, while the pump pistons are operated to move longitudinally into the cylinders by the cam 22.

At about the time that the cylinder 9 reaches the end of its working stroke, the roller 26 will strike the inclined surface 44 of the cam 27, the pump piston 12 will at this time be at the end 45 of the cylinder 9. The exhaust ports 36 will then be in communication with the space between the two

pistons thereby permitting the burnt gases to escape. When the roller 26 strikes the inclined surface 44, the lever 24 will rock and move the abutment piston 13 toward the pump piston 12 thereby forcing the gases out of the cylinder. The position of cylinder 10 illustrates this point. A little further movement of the disk will cause the roller 21 to strike the small cam surface 45^a of the cam 22 which will cause the lever 19 to rock and move the piston 12 or pump piston, to cover the exhaust ports 36. During this action the abutment piston 13 has not moved in its cylinder, but the roller 26 on its lever 24 has left the cam 27 and the other roller 46 on the said lever 24 has come in contact with a cam block 47. (The block 47 is shown in dotted lines in Fig. 1 diagrammatically, but is shown in full lines in Figs. 2 and 3 which show the said cam block as mounted on one of the bearings 48 for the shaft 2.) Cylinder 11 illustrates the position above referred to.

When the roller 46 on the lever 24 rides upon the cam 47, the abutment piston will be drawn or moved to the end 49 of its cylinder, which action will draw in an explosive mixture from the drum 50 through the duct 51 and valve casing 52. The valve casing communicates with an intake port 53 in each cylinder (see Fig. 4) which in turn is controlled by a valve 54.

The valve 54 is operated by the lever 24 by means of a resilient or flat spring rod 55 carried by said lever, so that said rod is given a reciprocating motion (Fig. 1). Said spring rod is provided with rollers 56 and 57 (see Fig. 4) which act upon a pivotal latch 58 having an arm 59 for closing the valve, an arm 60 for opening the valve, and an arm 61 which has a pin-and-slot connection with the valve for actuating it. When the valve 54 is closed, which it will be at all times excepting just after a cylinder has left the position shown by cylinder 11 in Fig. 1, the roller 57 will be positioned only part of the time as shown in Fig. 5 and as indicated in Fig. 1, or between the arm 59 and flange 62 on the valve casing. When the roller 57 is located as above described, the valve is kept closed, and the said roller will be in the said position at the time of an ignition. When, however, a roller 26 strikes the inclined surface 44, and a lever 24 is rocked to move the piston 13 inwardly toward the piston 12, the spring rod 55 will move also, and carry the roller 57 away from the latch 58, and to the first dotted position shown in Fig. 4, into a guide block 63, which maintains the spring in substantially its normal position, until the said roller reaches the second dotted position shown in Fig. 4 and leaves the guide block. The spring rod 55 will then be in the position shown in full lines in Fig. 4. At about

the time that the roller 57 leaves the guide block 63, the roller 56 will be positioned under the arm 60 of the latch, which up to this time, although roller 57 has left it, has remained in the position shown in Fig. 5. When the roller 57 reaches the end of the the guide block 63 the tension of the spring will be released, and the spring will fly outwardly to full line position, Fig. 4, causing the roller 56 to strike the arm 60, and move it outwardly, thereby opening the valve.

During the intake stroke of the piston 13, the spring rod 55 will move back with the lever 24 and will gradually be bent toward its normal position and put under tension by means of the block 64 on the lever 24. This tension will direct the roller 57 in between cam block 63 and the stem of valve 54, and bring said roller in substantial alignment with the space between flange 62 and arm 59. Just before the lever 24 reaches the end of its return stroke, the roller 57 will strike the arm 59, and close the valve; this action takes place while the cylinder is running from C to B. The block 65 on the lever 24 tends to reverse the tension of the spring rod 55 by pressing upon it when the lever 24 moves forward.

The valve casing 52 is provided with a valve 67 which closes the opening in the duct 51 when the valve 54 is closed. When the valve 54 opens, the valve 67 will also be opened by the suction of the piston. The valve 67 is closed by a flat spring 68. The intake valve port 53 is located at the exhaust end of the cylinder so that when explosion takes place, it is not open to the explosion chamber, and hence no back firing can take place.

It will be noticed that there are a number of exhaust ports 36. When the exhaust occurs there will be no sharp reports, as in the ordinary internal combustion engine, but more of a silent puff. During the compression period of the engine, the roller 21 will ride upon the cam 22 and force the piston 12 toward the piston 13. The shaft 2 may be provided with gears 66 for the transmission of power.

Obviously this invention is susceptible of various modifications, as parts may be omitted, parts added and parts altered, without departing from the broad scope and spirit of the invention.

What I claim as new is:—

1. In a rotary internal combustion engine, the combination of a hollow rotary shaft divided into two chambers for respectively receiving the explosive mixture and cooling air, cylinders carried by said shaft and to which said chambers lead, and means operated by the explosions in said cylinders, for rotating said shaft.

2. In an internal combustion engine, the combination of a cylinder mounted for ro-

tary movement, means for closing one end of said cylinder, a compression piston operable in the opposite end, said opposite end having an exhaust opening controlled by said piston, an abutment for said piston at the time of explosion, an incline leading to said abutment to impart a compressing movement to said piston, and movable means for acting on said piston to shut off said exhaust before said incline acts on said piston.

3. In an internal combustion engine, the combination of a rotary shaft, a plurality of cylinders mounted thereon, each of said cylinders being open at both ends, two pistons operable in each of said cylinders, one for compressing the explosive mixture and one for forcing out the burned gases, said pistons constituting end-closures for said cylinders, mechanism for moving the compression pistons preliminarily to cut off the exhaust, and means associated with said shaft to cause said compression pistons to compress and the other pistons to force out the burned gases.

4. In an internal combustion engine, the combination of a cylinder mounted in a position tangential to its path of rotation for rotary movement, and two pistons operable in said cylinder one for compressing the explosive mixture and one for forcing out the burned gases, and means co-operating with said compression piston outside of the path of rotation of said compression piston to resist movement of the same at the moment of explosion.

5. In an internal combustion engine, the combination of a cylinder mounted in a position tangential to its path of rotation for rotary movement, and two pistons operable in said cylinder, one of said pistons being a compression piston, a stationary abutment for one of said pistons at the time of explosion, said abutment being located outside of the path of rotation of said compression piston, and means for operating the other piston to force out the burned gases.

6. In an internal combustion engine, the combination of a cylinder mounted for rotary movement, and two pistons operable in said cylinder, an abutment for one of said pistons at the time of explosion, an incline leading to said abutment to impart a compressing movement to said piston, and means for operating the other piston to force out the burned gases.

7. In a rotary internal combustion engine, the combination of a rotary support, a cylinder mounted on said support, a movable end in said cylinder, means for controlling said end, abutment means fixed outside the path of rotation of said cylinder, a piston guided in said cylinder and adapted to compress the explosive mixture and cut off the exhaust during expansion, said piston being

- 4
 carried by said rotary support to a point in opposition to said abutment, said cylinder being open behind said piston, and means, in part located on the opposite movable end 5 of said cylinder, for igniting the compressed charge so that it acts to throw said cylinder and rotate its support in a direction away from said abutment.
8. In a rotary internal combustion engine, 10 the combination of a rotary support, a cylinder mounted on said support, abutment means fixed outside the path of rotation of said cylinder, a piston guided in said cylinder and adapted to compress the explosive mixture and cut off the exhaust during expansion, said piston being carried by said rotary support to a point in opposition to said abutment, a second piston movable in said cylinder, means for igniting the compressed charge so that it acts to throw said cylinder and rotate its support in a direction away from said abutment, and means for moving said second piston to press out the burned gases.
- 25 9. In a rotary internal combustion engine, the combination of a rotary support, a plurality of cylinders on said support, abutment means fixed outside the path of rotation, means for compressing the explosive mixture in and exhausting the burned gases from said cylinders, comprising for each cylinder pistons movable in the ends, means for moving one of said pistons to compress the explosive mixture against the other piston, means for moving the said other piston to press out the burned mixture, and means for exploding the mixture in said cylinder at a time when the first said piston is seated against said abutment.
- 30 40 10. In an internal combustion engine, the combination of a plurality of cylinders movable for work in one direction and each open at both ends, supporting means for said cylinders, two pistons operable in each cylinder and constituting closures for said ends, means at the outer ends of said cylinders and coöperating with one of said pistons of each cylinder to resist movement of the same at the moment of explosion, and means for operating the other piston of each cylinder to force out the burned gases.
11. In a rotary internal combustion engine, the combination of a rotary support, cylinders mounted thereon, two pistons in each cylinder, intake valves, means for controlling the pistons, one of which serves as a valve to control the exhaust, and means for mechanically controlling the movement of the intake valves alone, from said piston controlling means.
12. In an internal combustion engine, the combination of a cylinder mounted for rotary movement, said cylinder being open at both ends, two pistons operable in said cylinder, one for compressing the explosive mixture, and means for acting on the other piston to cause it to travel substantially the length of said cylinder to scavenge the cylinder and immediately following the scavenging to expose substantially the whole of the inner surface of said cylinder to a rush of cool air.
13. In an internal combustion engine, the combination of a cylinder, which is open at both ends, an annular inward abutment at one end of said cylinder, said abutment providing an opening which approximates the diameter of said cylinder, and two pistons operable in said cylinder, one for compressing the explosive mixture and the other constituting a scavenging piston, adapted to receive the shock of the explosion and to transmit it through its outer edge to said abutment.
